R. B. WHITESIDE

CONTAINER

Filed Aug. 29 1927

INVENTOR,
R. B. Whiteside;

BY

GE. Maynard
ATTORNEY.

UNITED STATES PATENT OFFICE.

ROBERT B. WHITESIDE, OF LOS ANGELES, CALIFORNIA.

DESIGN FOR A CONTAINER.

Application filed August 29, 1927. Serial No. 23,239. Term of patent 7 years.

To all whom it may concern:

Be it known that I, ROBERT B. WHITESIDE, a citizen of the United States, and a resident of Los Angeles, California, have invented a new, original, and ornamental Design for a Container, of which the following is a specification, reference being had to the accompanying drawing, forming a part hereof.

I claim:

The ornamental design for a container substantially as shown.

ROBERT B. WHITESIDE.
